UNITED STATES PATENT OFFICE.

ERCOLE LAURETI, OF NEW YORK, N. Y.

CIGARETTE CASE AND LIGHTER.

1,282,882.

Specification of Letters Patent. Patented Oct. 29, 1918.

Application filed September 8, 1917. Serial No. 190,398.

To all whom it may concern:

Be it known that I, ERCOLE LAURETI, a subject of the King of Italy, and a resident of the city of New York, borough of Manhattan, in the county and State of New York, have invented a new and Improved Cigarette Case and Lighter, of which the following is a full, clear, and exact description.

10 This invention relates to cigarette cases or the like and has particular reference to a combined cigarette case or holder and lighter providing a device whereby through the operation of one hand only the operator may 15 eject a cigarette from the case, light the same while being drawn from the case and close the case to return the same to his pocket.

Among the special objects therefore of the invention is to provide a cigarette case 20 adapted to hold a considerable number of cigarettes, said case having combined with it automatic lighting means so constructed or arranged with respect to the first mentioned part of the case as to make possible the lighting 25 of the cigarette while a portion of it is still within the case but with one end of the cigarette projected and grasped between the smoker's lips.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a perspective view showing the manner of use and operation of the improvement.

Fig. 2 is a side elevation of the device showing the relative position of the parts 45 with the taper ignited.

Fig. 3 is a rear edge view with all parts closed.

Fig. 4 is a vertical transverse section on the line 4—4 of Fig. 2.

50 Fig. 5 is a plan view.

Fig. 6 is a horizontal section on the line 6—6 of Fig. 2.

55 Fig. 7 is an elevation with the two main parts of the case swung open and indicating especially the means for manipulating the cigarettes in the main case;

Fig. 8 is a front elevation of parts in section on the line 8—8 of Fig. 2.

Fig. 9 is a vertical sectional detail on the line 9—9 of Fig. 8 indicating the ignition mechanism actuated by the swinging open of the lid.

Referring now more particularly to the drawings I show a construction comprising two main parts which may be identified for convenience of description as primary and secondary parts 10 and 11, respectively, hinged together at the front along a vertical axis 12. The primary part is arranged to constitute a receptacle for a series of 70 cigarettes C arranged horizontally and parallel to one another in a single layer. 13 indicates a spring pressed follower serving to hold the cigarettes advanced toward the top of the primary part 10 so that there shall always be one cigarette in alignment with a rear opening 14 at the upper end of the rear wall of the casing. Any suitable means may be provided to eject the cigarettes singly through the opening 14. For this purpose I 80 provide an ejector 15 having an outside finger piece at the top of the device and a forwardly and downwardly projecting claw 15' which lies normally against the inner wall of the front part of the casing in position to abut squarely against the inner end of the uppermost cigarette. A spring 16 acts upon the ejector to normally hold it in the position just indicated and against the force of this spring the ejector may be operated by the smoker's finger rearwardly to eject the cigarette far enough through the opening 14 to be grasped between his lips.

The secondary part 11 of the device comprises two features, namely, the igniting device and an auxiliary holder 17 for an extra supply of cigarettes shown at C' and arranged vertically. The igniting device includes a tank 18 for benzene or other suitable inflammable liquid from which a wick 19 100 leads through the top and is so positioned that its upper end will be in the field of a spark from any suitable or well known sparking mechanism 20 made operative by the snapping open of a spring operated lid 105 21 held normally closed by means of a catch 22 adapted to be pressed at the front edge of the case by the operator's finger after the ejector 15 has been actuated. The secondary portion of the case includes an inner wall or partition 23 having a window 24 formed therethrough adjacent to the taper

19 or directly between said taper and the exposed inner end of the cigarette that has been projected outwardly through the opening 14 as a result of the actuation of the ejector 15. This will be understood from Fig. 7 in which the cigarette is indicated as partially ejected, the ejector having been moved approximately half way. In the top of the lid 21 is provided a cap 25 which is adapted to slip over the wick 19 when the lid 21 is closed again, thereby snuffing the flame. The supply of oil for the tank 18 may be replenished through any suitable vent, the same being indicated in this instance as being closed by a screw plug 26 at the bottom.

15 A lid 27 is hinged at 28 to the secondary portion of the device providing for access to the auxiliary holder 17.

20 From the foregoing specific description of the construction, its method of operation may be briefly summarized as follows: A smoker equipped with one of these combination devices withdraws it from his pocket and grasping the same between his thumb and last three fingers of one hand, operates the ejector 15 with his index finger with the result that the uppermost cigarette is projected through the opening 14 far enough for 25 the extending end to be grasped by and between his lips. The index finger is then shifted to depress the catch 22 setting the lid 21 free to snap open freely under the force of its spring. This action of the lid 30 causes a spark from the igniting device to light the flame at 19. The operator then, with the cigarette grasped between his lips, inhales through the cigarette in the usual manner causing the flame from the torch 19 35 to pass inwardly through the window 24 where it is drawn directly against the inner end of the cigarette whose other end is between his lips. See Fig. 8. This flame has no effect on the next cigarette or any other 40 in the case because it is drawn directly into the exposed end of the uppermost cigarette. When this cigarette is lighted the operator using the same index finger will snap the 45

lid 21 shut, extinguishing the flame of the torch and leaving the case closed and ready to be put into his pocket or subject to subsequent delivery of another cigarette. It will be understood that at any time after the cigarette is lighted the smoker will complete the delivery or ejection of the cigarette 55 from the case by simply carrying the case bodily away from his face leaving the cigarette between his lips. It will thus be seen that I provide a simple, convenient and reliable combination smoker's case through the 60 use of which with one hand only the smoker may deliver and light his cigarettes.

I claim:

1. A cigarette case and lighter, comprising two hinged members, one member being 65 adapted to hold cigarettes and provided with an opening in its inner face and an opening in one end, near the top, means for holding the uppermost cigarette in alinement with the end opening, and means for projecting a 70 cigarette through said opening, the other member having an igniting device, a cover operating the igniting device upon opening the same, and having an opening in its inner face adjacent its hinged edge and lying opposite the opening in the inner face of the first member.

2. A cigarette holder and lighter, comprising a casing adapted to contain cigarettes, said casing having an opening in its 80 inner face and an opening in one end, a spring pressed follower in the casing, a sliding and spring pressed ejector on the top of the casing, and having a member extending into the casing to engage the end of a cigarette to project it through the end opening of the casing, a member hinged to the casing to fold against the same over the opening thereof and having an opening adjacent to its hinged edge and lying opposite the 85 inner end of the opening in the inner face of the casing, said member carrying an igniting device adjacent the opening thereof and provided with a hinged cover operating the igniting device.

ERCOLE LAURETI.
